Primary Examiner — Jennifer Rivard*Assistant Examiner* — Catherine S Posthauer*(74) Attorney, Agent, or Firm* — George C. Rondeau, Jr.;
Davis Wright Tremaine LLP(57) **CLAIM**

The ornamental design for a beverage container lid, as shown and described.

DESCRIPTION

FIG. 1 is a top perspective view of a third embodiment thereof.

FIG. 2 is a bottom perspective view thereof.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof; and,

FIG. 8 is a bottom plan view thereof.

The broken lines are shown for the purpose of illustrating the boundaries of the claim, as well as parts of the article, none of which form part of the claim.

1 Claim, 6 Drawing Sheets---
